US00D479198S

(12) United States Design Patent **(10) Patent No.:** **US D479,198 S**
Zhu **(45) Date of Patent:** **** Sep. 2, 2003**

(54) ELECTRICAL CONNECTOR

(75) Inventor: **Jian-Guo Zhu, Kunsan (CN)**

(73) Assignee: **Hon Hai Precision Ind. Co., Ltd.,**
Taipei Hsien (TW)

(**) Term: **14 Years**

(21) Appl. No.: **29/158,936**

(22) Filed: **Apr. 12, 2002**

(30) Foreign Application Priority Data

Mar. 29, 2002 (TW) 91301386

(51) LOC (7) Cl. **13-03**

(52) U.S. Cl. **D13/147**

(58) Field of Search D13/146, 147,
D13/154; 439/607, 610, 660
